(57) **ABSTRACT**

A downlight apparatus includes a light source, a light housing and a stop unit. The driver box is used for storing a driver. The driver is connected to an external power source to generate a driving current to the light source. The driver box has a wall with an installation escape. The light housing has a light holder and a rim. The light source is stored in the light holder. The rim defines a light opening for a light of the light source to escape. The stop unit is fixed to the installation escape. The stop unit has a switch holder and a wire holder. A manual switch is placed in the switch holder and an enlarged wire head of an power wire is placed in the wire holder. An operation part of the manual switch is exposed outside the driver box. The manual switch is connected to the driver for adjusting a setting of the driver.

DOWNLIGHT APPARATUS

FIELD

The present invention is related to a downlight apparatus, and more particularly related to a downlight apparatus with a convenient assembly design.

BACKGROUND

The time when the darkness is being lighten up by the light, human have noticed the need of lighting up this planet. Light has become one of the necessities we live with through the day and the night. During the darkness after sunset, there is no natural light, and human have been finding ways to light up the darkness with artificial light. From a torch, candles to the light we have nowadays, the use of light have been changed through decades and the development of lighting continues on.

Early human found the control of fire which is a turning point of the human history. Fire provides light to bright up the darkness that have allowed human activities to continue into the darker and colder hour of the hour after sunset. Fire gives human beings the first form of light and heat to cook food, make tools, have heat to live through cold winter and lighting to see in the dark.

Lighting is now not to be limited just for providing the light we need, but it is also for setting up the mood and atmosphere being created for an area. Proper lighting for an area needs a good combination of daylight conditions and artificial lights. There are many ways to improve lighting in a better cost and energy saving. LED lighting, a solid-state lamp that uses light-emitting diodes as the source of light, is a solution when it comes to energy-efficient lighting. LED lighting provides lower cost, energy saving and longer life span.

The major use of the light emitting diodes is for illumination. The light emitting diodes is recently used in light bulb, light strip or light tube for a longer lifetime and a lower energy consumption of the light. The light emitting diodes shows a new type of illumination which brings more convenience to our lives. Nowadays, light emitting diode light may be often seen in the market with various forms and affordable prices.

After the invention of LEDs, the neon indicator and incandescent lamps are gradually replaced. However, the cost of initial commercial LEDs was extremely high, making them rare to be applied for practical use. Also, LEDs only illuminated red light at early stage. The brightness of the light only could be used as indicator for it was too dark to illuminate an area. Unlike modern LEDs which are bound in transparent plastic cases, LEDs in early stage were packed in metal cases.

In 1878, Thomas Edison tried to make a usable light bulb after experimenting different materials. In November 1879, Edison filed a patent for an electric lamp with a carbon filament and keep testing to find the perfect filament for his light bulb. The highest melting point of any chemical element, tungsten, was known by Edison to be an excellent material for light bulb filaments, but the machinery needed to produce super-fine tungsten wire was not available in the late 19th century. Tungsten is still the primary material used in incandescent bulb filaments today.

Early candles were made in China in about 200 BC from whale fat and rice paper wick. They were made from other materials through time, like tallow, spermaceti, colza oil and beeswax until the discovery of paraffin wax which made

production of candles cheap and affordable to everyone. Wick was also improved over time that made from paper, cotton, hemp and flax with different times and ways of burning. Although not a major light source now, candles are still here as decorative items and a light source in emergency situations. They are used for celebrations such as birthdays, religious rituals, for making atmosphere and as a decor.

Illumination has been improved throughout the times. Even now, the lighting device we used today are still being improved. From the illumination of the sun to the time when human can control fire for providing illumination which changed human history, we have been improving the lighting source for a better efficiency and sense. From the invention of candle, gas lamp, electric carbon arc lamp, kerosene lamp, light bulb, fluorescent lamp to LED lamp, the improvement of illumination shows the necessity of light in human lives.

There are various types of lighting apparatuses. When cost and light efficiency of LED have shown great effect compared with traditional lighting devices, people look for even better light output. It is important to recognize factors that can bring more satisfaction and light quality and flexibility.

Downlight devices are widely used in various places. It is beneficial to find out improvements of downlight devices to provide a more convenient and more safe downlight products.

In addition, it is important to provide a convenient assembly structure. The structure includes complexity reducing during manufacturing and during installation.

It is also important to consider heat dissipation and water proof.

It is also important to consider element design. Even small changes can make installation and assembly more convenient, which may also reduce manufacturing cost.

Therefore, it is beneficial to design a light device with multiple advantages. Downlight devices are widely used in various places. It is beneficial to find out improvements of downlight devices to provide a more convenient and more safe downlight products.

SUMMARY

In some embodiments, a downlight apparatus includes a light source, a light housing and a stop unit.

The driver box is used for storing a driver.

The driver is connected to an external power source to generate a driving current to the light source.

The driver box has a wall with an installation escape.

The light housing has a light holder and a rim.

The light source is stored in the light holder.

The rim defines a light opening for a light of the light source to escape.

The stop unit is fixed to the installation escape.

The stop unit has a switch holder and a wire holder.

A manual switch is placed in the switch holder and an enlarged wire head of an power wire is placed in the wire holder.

An operation part of the manual switch is exposed outside the driver box.

The manual switch is connected to the driver for adjusting a setting of the driver.

In some embodiments, the installation escape is a first U-shape concave on the wall of the driver box. The stop unit is inserted into the first U-shape concave along two lateral edges of the first U-shape concave.

In some embodiments, the stop unit has two lateral grooves as tracks for sliding the two lateral edges of the first U-shape concave to attach the stop unit to the driver box.

In some embodiments, a front plate and a back plate of the stop unit form the two lateral grooves.

The front plate is closer to outside of the driver box than the back plate.

The back plate has a larger diameter than the front plate to prevent water to move in the drive box.

In some embodiments, the switch holder is a second concave U-shape concave of the stop unit.

The manual switch is inserted and fixed to the second U-shape concave.

In some embodiments, the switch holder has two switch grooves for inserting and fixing two lateral edges of the manual switch.

In some embodiments, the switch holder has a front space and a back space.

The back space is used for storing a switch board.

The front space is used for storing an operation unit of the manual switch.

In some embodiments, the wire holder is a third U-shape concave of the stop unit.

The enlarged wire head is inserted and fixed to the third U-shape concave.

In some embodiments, the downlight apparatus may also include a electrode socket.

The light source includes a light source plate mounted with LED modules.

The light source plate has a plate hole for inserting and fixing the electrode socket.

In some embodiments, the electrode socket has an insulation base with a first electrode groove and a second electrode groove.

The insulation base defines a first electrode hole and second electrode hole, the electrode socket has a first metal unit and a second metal unit, the first metal unit and the second metal unit respectively have elastic receivers for inserting a driver electrode electrically connecting to the driver.

10 In some embodiments, the first metal unit and the second metal unit respectively have an elongated bar respectively extending along the first electrode groove and the second electrode groove.

The first metal unit and the second metal unit respectively have a contact end for electrically connecting to the LED modules on the light source plate.

15 In some embodiments, the first electrode groove and the second electrode groove are above a top surface of the light source plate.

20 In some embodiments, the contact ends extend along an edge of the insulation to be welded to light source electrodes of the light source plate.

In some embodiments, electrode receiver has an elastic clip for inserting the driver electrode.

25 In some embodiments, the elastic clip is a reverse hook with a smaller force on attaching the driver electrode to the electrode receiver for detaching the driver electrode off the electrode receiver.

30 In some embodiments, any metal part of the electrode socket and the driver electrode is kept longer than 4 mm from any metal part of the light source plate.

In some embodiments, any metal part of the electrode socket and the driver electrode is kept longer than 4 mm from any metal part of the light source plate.

35 In some embodiments, the insulation base has a light reflective layer for redirecting the light of the light source.

In some embodiments, the electrode socket has an antenna socket for plugging an antenna.

40 In some embodiments, the insulation base has a middle protrusion separating the first electrode groove and the second electrode groove.

DETAILED DESCRIPTION

In some embodiments, a downlight apparatus includes a light source **6014**, a driver box **6001**, a light housing **6007** and a stop unit **6015**. The driver box **6001** is used for storing a driver **6019**. The driver **6019** is connected to an external power source to generate a driving current to the light source **6014**. The driver **6019** may include a rectifier, a transformer, a filter, a current source, a protection circuit and other components. The driver box **6001** has a wall **6025** with an installation escape **6002**. The light housing **6007** has a light holder **6005** and a rim **6006**. The light source **6014** is stored in the light holder **6005**. The rim **6006** defines a light opening **6026** for a light of the light source **6014** to escape. The stop unit **6015** is fixed to the installation escape **6002**. The stop unit **6015** has a switch holder **6010** and a wire holder **6011**. A manual switch **6008** is placed in the switch holder **6010** and an enlarged wire head **6012** of an power wire **6013** is placed in the wire holder **6011**. An operation part **6009** of the manual switch **6008** is exposed outside the driver box **6001**. The manual switch **6008** is connected to the driver **6019** for adjusting a setting of the driver **6019**. In some embodiments, the installation escape **6002** is a first U-shape concave on the wall of the driver box **6001**.

The stop unit **6015** is inserted into the first U-shape concave along two lateral edges of the first U-shape concave.

FIG. 74 shows such an example. In FIG. 74, the driver box **972** has a first U-shape concave **9713** for inserting the stop unit **9721**.

In FIG. 78, the stop unit has two lateral grooves **975** as tracks for sliding the two lateral edges of the first U-shape concave to attach the stop unit to the driver box.

In FIG. 78, a front plate **9792** and a back plate **9791** of the stop unit form the two lateral grooves **975**.

The front plate **9792** is closer to outside of the driver box than the back plate **9791**.

The back plate **9791** has a larger diameter than the front plate **9792** to prevent water to move in the drive box.

In some embodiments, the switch holder is a second concave U-shape concave of the stop unit.

The manual switch is inserted and fixed to the second U-shape concave **973**.

In some embodiments, the switch holder has two switch grooves **976** for inserting and fixing two lateral edges of the manual switch.

In some embodiments, the switch holder has a front space **97303** and a back space **97301**.

The back space **97301** is used for storing a switch board. For example, a manual switch is a switch board mounted with a lever or a slider.

The front space **97301** is used for storing an operation unit of the manual switch.

In some embodiments, the wire holder is a third U-shape concave **974** of the stop unit.

The enlarged wire head is inserted and fixed to the third U-shape concave.

In FIG. 87, the downlight apparatus may also include a electrode socket **6003**.

The light source includes a light source plate **6031** mounted with LED modules **6032**.

The light source plate **6031** has a plate hole for inserting and fixing the electrode socket **6003**.

In FIG. 28, a plate hole **9991** is used inserting the electrode socket **9992**.

In FIG. 25, the electrode socket **9912** has an insulation base **991** with a first electrode groove and a second electrode groove **9910**.

The insulation base defines a first electrode hole and second electrode hole **9911**.

In FIG. 26, the electrode socket has a first metal unit and a second metal unit **9922**. The first metal unit and the second metal unit **9922** respectively have elastic receivers **99212** for inserting a driver electrode electrically connecting to the driver.

In some embodiments, the first metal unit and the second metal unit **9922** respectively have an elongated bar **99227** respectively extending along the first electrode groove and the second electrode groove.

The first metal unit and the second metal unit respectively have a contact end **99228** for electrically connecting to the LED modules on the light source plate.

In some embodiments, the first electrode groove and the second electrode groove are above a top surface of the light source plate, as illustrated in FIG. 28.

In some embodiments, the contact ends extend along an edge of the insulation to be welded to light source electrodes of the light source plate.

In FIG. 26, electrode receiver **99212** has an elastic clip **99211** for inserting the driver electrode.

In some embodiments, the elastic clip **99211** is a reverse hook with a smaller force on attaching the driver electrode to the electrode receiver than detaching the driver electrode off the electrode receiver

5 In some embodiments, any metal part of the electrode socket and the driver electrode is kept longer than 4 mm from any metal part of the light source plate.

In some embodiments, any metal part of the electrode socket and the driver electrode is kept longer than 1 mm from any metal part of the light source plate.

For example, the L1 and L2 distance are longer than 4 mm or 1 mm depending on whether the downlight device is used in water environment or not.

15 In some embodiments, the insulation base has a light reflective layer for redirecting the light of the light source. For example, a surface of the insulation base is painted with white paint so as to increase a light reflective rate, particularly when the insulation base is protruding above the surface for mounting the LED modules, which may cause shadow or undesired effect.

In some embodiments, the electrode socket has an antenna socket **6041** for plugging an antenna. For example, an antenna is plugged to the antenna socket **6041**.

In FIG. 25, the insulation base has a middle protrusion **99101** separating the first electrode groove and the second electrode groove.

The foregoing description, for purpose of explanation, has been described with reference to specific embodiments. However, the illustrative discussions above are not intended to be exhaustive or to limit the invention to the precise forms disclosed. Many modifications and variations are possible in view of the above teachings.

The embodiments were chosen and described in order to best explain the principles of the techniques and their practical applications. Others skilled in the art are thereby enabled to best utilize the techniques and various embodiments with various modifications as are suited to the particular use contemplated.

Although the disclosure and examples have been fully described with reference to the accompanying drawings, it is to be noted that various changes and modifications will become apparent to those skilled in the art. Such changes and modifications are to be understood as being included within the scope of the disclosure and examples as defined by the claims.

The invention claimed is:

1. A downlight apparatus, comprising:

a light source;

a driver box for storing a driver, wherein the driver is connected to an external power source to generate a driving current to the light source, wherein the driver box has a wall with an installation escape;

a light housing with a light holder and a rim, wherein the light source is stored in the light holder, wherein the rim defines a light opening for a light of the light source to escape; and

a stop unit fixed to the installation escape, wherein the stop unit has a switch holder and a wire holder, wherein a manual switch is placed in the switch holder and an enlarged wire head of a power wire is placed in the wire holder, wherein an operation part of the manual switch is exposed outside the driver box, wherein the manual switch is connected to the driver for adjusting a setting of the driver.

2. The downlight apparatus of claim 1, wherein the installation escape is a first U-shape concave on the wall of the driver box, the stop unit is inserted into the first U-shape concave along two lateral edges of the first U-shape concave.

3. The downlight apparatus of claim 2, wherein the stop unit has two lateral grooves as tracks for sliding the two lateral edges of the first U-shape concave to attach the stop unit to the driver box.

4. The downlight apparatus of claim 3, wherein a front plate and a back plate of the stop unit form the two lateral

11

grooves, wherein the front plate is closer to outside of the driver box than the back plate, wherein the back plate has a larger diameter than the front plate to prevent water to move in the drive box.

5. The downlight apparatus of claim 2, wherein the switch holder is a second concave U-shape concave of the stop unit, wherein the manual switch is inserted and fixed to the second U-shape concave.

6. The downlight apparatus of claim 5, wherein the switch holder has two switch grooves for inserting and fixing two lateral edges of the manual switch.

7. The downlight apparatus of claim 6, wherein the switch holder has a front space and a back space, wherein the back space is used for storing a switch board, wherein the front space is used for storing an operation unit of the manual switch.

8. The downlight apparatus of claim 5, wherein the wire holder is a third U-shape concave of the stop unit, wherein the enlarged wire head is inserted and fixed to the third U-shape concave.

9. The downlight apparatus of claim 1, further comprising a electrode socket, wherein the light source comprises a light source plate mounted with LED modules, wherein the light source plate has a plate hole for inserting and fixing the electrode socket.

10. The downlight apparatus of claim 9, wherein the electrode socket has an insulation base with a first electrode groove and a second electrode groove, wherein the insulation base defines a first electrode hole and second electrode hole, the electrode socket has a first metal unit and a second metal unit, the first metal unit and the second metal unit respectively have elastic receivers for inserting a driver electrode electrically connecting to the driver.

11. The downlight apparatus of claim 10, wherein the first metal unit and the second metal unit respectively have an elongated bar respectively extending along the first electrode

12

groove and the second electrode groove, wherein the first metal unit and the second metal unit respectively have a contact end for electrically connecting to the LED modules on the light source plate.

5. The downlight apparatus of claim 11, wherein the first electrode groove and the second electrode groove are above a top surface of the light source plate.

13. The downlight apparatus of claim 12, wherein the contact ends extend along an edge of the insulation to be welded to light source electrodes of the light source plate.

14. The downlight apparatus of claim 10, wherein electrode receiver has an elastic clip for inserting the driver electrode.

15. The downlight apparatus of claim 14, wherein the elastic clip is a reverse hook with a smaller force on attaching the driver electrode to the electrode receiver than detaching the driver electrode off the electrode receiver.

16. The downlight apparatus of claim 10, wherein any metal part of the electrode socket and the driver electrode is kept longer than 4 mm from any metal part of the light source plate.

17. The downlight apparatus of claim 10, wherein any metal part of the electrode socket and the driver electrode is kept longer than 1 mm from any metal part of the light source plate.

18. The downlight apparatus of claim 10, wherein the insulation base has a light reflective layer for redirecting the light of the light source.

19. The downlight apparatus of claim 10, wherein the electrode socket has an antenna socket for plugging an antenna.

20. The downlight apparatus of claim 10, wherein the insulation base has a middle protrusion separating the first electrode groove and the second electrode groove.
